GOLF CLUB GRIP

Alexander Cunningham, Glenview, and Robert E.
Dyer, Chicago, Ill.

Application January 11, 1937, Serial No. 120,014

2 Claims. (Cl. 273—81)

The present invention relates to golf clubs and more particularly to a hand grip for golf clubs having certain novel features that will be hereinafter more fully explained by means of which 5 the ability of the player using the club to direct the movement of the club such as a putter in a straight line is improved.

In the use of a putter and similar clubs, the player has difficulty in properly aligning the club 10 and in properly positioning his hands and fingers upon the club so as to maintain this alignment. One tendency, due to this difficulty, is for the player to grip the club too tightly, thus putting the muscles under tension and interfering with 15 the control he is capable of exercising over the speed of travel and direction of travel of the club. It is well known that, if the club handle can be held in the proper position with the muscles relaxed in the arms, the player has a much 20 better opportunity of controlling both the speed and direction of the stroke.

The present invention contemplates the provision of a hand grip which is so formed as first 25 to facilitate aligning the club and the body of the player so that the swing of the club will be in the right direction, and second to cause the hand and fingers of the player to grip the club in such a fashion that the right and left hands will be in 30 opposition to each other with the wrists substantially straight and with the hands aligned with the direction in which the club should swing. In the movement of the hands and the club, there is no turning or twisting of the hands that would 35 tend to throw the club head out of line. The positioning of the hands required with the present hand grip is such as to prevent the player from gripping the club too tightly and to prevent him from placing the hands in an improper position.

40 In carrying out the present invention, it is contemplated to build up curved projections at the sides of the club shaft which projections are in a plane perpendicular to the plane of the club head or substantially so. These projections, 45 however, are so arranged in conjunction with a flat front face on the club as to position the hands, that is, the forward hand and the rear hand of the player, opposite each other with respect to the club shaft, and with the rear hand below the forward hand.

In the description and in the claims, the hands and fingers of the player are referred to together as the forward hand meaning the hand on the side of the club toward the direction in which the 55 ball is to be driven, and the rear hand on the

opposite side of the club. The terms "forward" and "forwardly", when used with respect to the hand grip, mean direction toward which the striking face of the club head faces; conversely "rearward" and "rearwardly" mean the direction 5 opposite that toward which the striking face of the club head faces. For right handed players, the forward hand is the left hand, but, for left handed players, the forward hand is the right hand. 10

The features and advantages of the invention will appear more clearly from the following description reference being had to the accompanying drawing wherein—

Fig. 1 is a view in front elevation of a club 15 showing how the hands of a player grip it;

Fig. 2 is a view in side elevation;

Fig. 3 is an enlarged front view of the hand grip;

Fig. 4 is a top plan view looking at the club 20 from point 4—4 in Fig. 3; and

Fig. 5 is a sectional view on the line 5—5 of Fig. 3.

Referring now to the drawing, the numeral 10 refers to a golf club head which is carried by a 25 shaft 11. The shaft 11 has at its upper end a hand grip 12 which is the subject matter of the present invention. The club head 10, as shown best by Fig. 4, extends at right angles to a flattened front face 13 of the hand grip 12. This 30 flattened front face 13 extends throughout substantially the entire length of the hand grip 12 and is so positioned as to be readily engageable by a player's thumbs as indicated at 14 and 15. The forward hand 16 of the player engages with 35 the upper portion of the hand grip which is enlarged, as shown best in Fig. 4, on the forward side of the club shaft at 17. The enlarged portion 17 is smoothly curved along a line 18 and is rounded as indicated at 19 (see Fig. 4) so as to fit 40 snugly in the palm of the forward hand 16. The fingers 20 of the forward hand extend around to the back or rear side of the club shaft and are partially covered by the rear hand 21.

Below the portion 17 and opposite to it, the hand grip 12 is provided with an enlargement 22 which is quite similar in shape to the enlargement 17 and along the surface 23 thereof. This portion 22 of the hand grip is adapted to seat in the palm 45 of the rear hand 21 and to force this hand out at substantially the same angle as the forward hand 16. Preferably, the enlargements 17 and 22 are made such as to produce an angle between 50 the hands and the club shaft that will result in 55

the wrists of the player being substantially straight.

Since the portions 17 and 22 are opposite except that one is higher up on the shaft than the other, it is evident that the hands, in gripping them with the thumbs placed upon the flat front face 13, will be held in a natural opposed relation with respect to each other with none of the muscles used to rotate the hands being put under tension.

This positioning of the hands is highly essential in that it avoids any tendency or desire on the part of the player to turn the hands out of this correct relaxed position. With the hands so positioned, the stroke of the club is merely a matter of bringing two opposing sets of muscles into play, no tendency to rotate the club shaft being present. The player in putting, therefore, need only properly align the shaft and club head with the ball and the cup, and then properly align himself with the front face 13 of the club head to be in position to correctly swing the club without putting any appreciable amount of pressure upon the club by the hands. The players can thus relax in putting to a much greater degree than where it is necessary to grip a club shaft.

It will be noted that the hand grip 12 is enlarged at 24 on the forward side. This enlargement performs two functions. It provides a wide support for the thumb 14, making it easier to position the hands on the hand grip, and in addition it builds up the edge 25 opposite the edge 23 so that the edge 25 positions fingers 26 of the rear hand much in the same fashion as the fingers 20 are positioned by the portion 27 opposite the enlargement 17.

From the above description, it is believed that the construction and advantages of this device will be readily apparent to those skilled in this art.

It is also believed to be obvious that minor modi-

fications may be made from the exact details shown and described without departing from the scope of the invention as defined in the claims.

Having thus described our invention, what we claim as new and desire to secure by Letters Patent is:

1. A golf club having a head and a shaft for said head, a hand grip on the shaft having a flattened front face, said hand grip having upper and lower rounded enlargements at the left hand and right hand edges of said flattened face, the left hand enlargement being extended farther forwardly from the center line of the shaft than the right hand enlargement is extended rearwardly from the center line of the shaft whereby the fingers of the left hand of a player when fitted inside the upper portion of the right hand combine with the right hand enlargement to force the upper portion of the right hand out at substantially the same angle to the shaft as the upper enlargement forces the upper part of the left hand to take with respect to the shaft.

2. The combination in a golf club of a shaft, a head at one end thereof, a hand grip on the other end thereof, and having means thereon directing the forward and rear hands of a player into opposite positions, said means comprising a forwardly directed enlargement at the forward side only of the grip for seating in the palm of the forward hand, and a rearwardly directed enlargement at the rearward side only of the grip and spaced below the first named enlargement for seating in the palm of the rear hand, said enlargements cooperating to spread the palms of the player's hands apart and thereby restrain rotative displacement of the hands with respect to the forearms.

ALEXANDER CUNNINGHAM.
